(57) **CLAIM**

The ornamental design for a cooking utensil splatter lid, as shown.

DESCRIPTION

FIG. 1 is a top view of the invention.

FIG. 2 is a bottom view.

FIG. 3 is a front view, the rear view being identical; and, FIG. 4 is a right side view, the left side view being identical. The broken line showing of the handle is for illustrative purposes only and forms no part of the claimed design.
